US00D758063S

(12) **United States Design Patent**
Naka et al.(10) **Patent No.:** **US D758,063 S**
(45) **Date of Patent:** **** Jun. 7, 2016**(54) **CROCHET HOOK**(71) Applicant: **Yachiyo Industrial Co., Ltd.,**
Hiroshima-shi, Hiroshima (JP)(72) Inventors: **Namiko Naka**, Hiroshima (JP);
Tatsuhsia Nomura, Hiroshima (JP);
Kiyoko Hashikawa, Hiroshima (JP)(73) Assignee: **YACHIYO INDUSTRIAL CO., LTD.,**
Hiroshima-shi (JP)(**) Term: **14 Years**(21) Appl. No.: **29/512,688**(22) Filed: **Dec. 22, 2014**(30) **Foreign Application Priority Data**

Aug. 12, 2014 (JP) D2014-017652

JP D1269814 S 5/2006
JP D1366058 S 8/2009
JP D1431686 S 1/2012*Primary Examiner* — John Windmuller*Assistant Examiner* — Steven Czyz(74) *Attorney, Agent, or Firm* — Westerman, Hattori,
Daniels & Adrian, LLP(57) **CLAIM**An ornamental design for a crochet hook, as shown and
described.**DESCRIPTION**FIG. 1 is a front view of a crochet hook showing our new
design, the rear being a mirror image thereof;

FIG. 2 is a plan view thereof;

FIG. 3 is a bottom view thereof;

FIG. 4 is a right side view thereof;

FIG. 5 is a left side view thereof;

FIG. 6 is a cross-sectional view taken along line 6-6 of FIG. 1;

FIG. 7 is a cross-sectional view taken along line 7-7 of FIG. 1;

FIG. 8 is a cross-sectional view taken along line 8-8 of FIG. 1;

FIG. 9 is a cross-sectional view taken along line 9-9 of FIG. 1;

FIG. 10 is a cross-sectional view taken along line 10-10 of
FIG. 1;FIG. 11 is a cross-sectional view taken along line 11-11 of
FIG. 6;FIG. 12 is a cross-sectional view taken along line 12-12 of
FIG. 6; and,

FIG. 13 is a perspective view thereof.

The broken lines depict portions of the article that form no
part of the claimed design.**1 Claim, 5 Drawing Sheets**---
